US00D585737S

(12) United States Design Patent
Double et al.

(10) Patent No.: US D585,737 S
(45) Date of Patent: * Feb. 3, 2009

(54) SLOTTED CONTAINER

(75) Inventors: Matthew Double, San Diego, CA (US);
Michael Alan Carrier, San Diego, CA (US); David Lochner, Manhattan Beach, CA (US)

(73) Assignees: Sony Corporation, Tokyo (JP); Sony Electronics Inc., Park Ridge, NJ (US)

() Term: 14 Years

(21) Appl. No.: 29/319,396

(22) Filed: Jun. 9, 2008

(51) LOC (9) Cl. 09-03

(52) U.S. Cl. D9/432

(58) Field of Classification Search D9/430-433, D9/414, 418, 420-423, 435, 560, 561; D3/201, D3/272, 273, 305; 206/278, 297, 299, 320, 206/339, 433, 769, 770, 775, 776, 781, 782, 206/822; 229/100, 103.3, 104-106, 107, 229/108, 108.1, 110, 111, 112, 115, 117.16, 229/120, 125.015, 120.32, 133.24, 122.29, 229/124, 160.1, 162.1, 162.6, 163, 182.1, 229/201, 406, 407, 902, 904, 906, 922, 930, 229/939, 942

(57) CLAIM

The ornamental design for the slotted container, as shown and described.

DESCRIPTION

FIG. 1 is a perspective view of the slotted container;
FIG. 2 is a left side elevational view of the slotted container;
FIG. 3 is a front view of the slotted container;
FIG. 4 is a bottom plan view of the slotted container;
FIG. 5 is a top plan view of the slotted container;
FIG. 6 is a rear view of the slotted container; and,
FIG. 7 is a right side elevational view of the slotted container.
